F. McLAUGHLIN

DETACHABLE BIT FOR COAL AUGERS

Filed July 5, 1922

Patented Feb. 13, 1923.

1,445,097

UNITED STATES PATENT OFFICE.

FRED McLAUGHLIN, OF CANTON, ILLINOIS.

DETACHABLE BIT FOR COAL AUGERS.

Application filed July 5, 1922. Serial No. 572,890.

To all whom it may concern:

Be it known that I, FRED McLAUGHLIN, a citizen of the United States, residing at Canton, in the county of Fulton and State of Illinois, have invented certain new and useful Improvements in Detachable Bits for Coal Augers, of which the following is a specification, reference being had to the accompanying drawings.

10 This invention relates to detachable bits for boring or drilling purposes, and particularly to detachable bits for coal augers. It is common practice in coal mining for the bit to be turned from a part of the auger. 15 While coal augers are made of ordinary auger steel, this material is not adapted for forming cutting bits, and the bit turned from a part of the auger is, of course, of steel no better than the auger itself. On the 20 other hand, to make the entire auger of a special steel of a quality which would stand wear and abrasion would make the cost prohibitive, as the need for a superior steel is in the bit only. The bit turned from a part 25 of the auger is not of a character and temper that will defy punishment, particularly in drilling through sulphur and other hard substances. Bits of this character wear rapidly even in soft coal, and the cutting 30 edges of the bits can only be kept sharp by constant filing. Therefore, the long augers have to be sent out of the mine whenever 35 requiring new bits and each re-sharpening process shortens the auger. It is necessary, therefore, for a miner to have with him a number of augers so in case one bit auger becomes too dull for use it may be sent to the surface while another auger is used.

35 The object of my invention is to provide 40 a detachable bit adapted to be clamped upon the extremity of the auger, this detachable bit being made of high duty steel so as to secure the greatest possible toughness and cutting qualities for the bit so that the bit 45 will thereby stay sharp and outwear a large number of bits made from ordinary steel.

45 A further object is to provide a bit which may be readily applied to ordinary coal augers with but slight modification in the 50 shape of the coal auger and so constructed that the length and angles of its cutting edges are such as to produce a fast cutting auger and easy drilling.

55 A still further object is to provide a bit of this character which is so formed that

it may be relatively cheaply made by stamping and so formed that all that is necessary to do to fit the auger to the bit is to somewhat flatten the extremity of the auger, which may be readily done by blacksmithing.

Another object is to provide wings detachably engaged with the bit which will act to guide the material into the threads of the auger, and which may be readily removed and replaced when worn or injured.

Still another object is to make the cutting bits of two interchangeable parts of a standard size, which are readily applied to all types or makes of coal augers, both old and new.

Other objects will appear in the course of the following description.

My invention is illustrated in the accompanying drawings, wherein:—

75 Figure 1 is a side elevation of a coal auger with my improved bit applied thereto;

Figure 2 is an end view of the bit shown in Figure 1;

Figure 3 is a perspective view of the bit 80 detached from the auger;

Figure 4 is a perspective view of one of the bit sections;

Figure 5 is an end view of the auger showing how the auger is flattened for use with 85 my detachable bit.

Referring to these drawings, wherein A designates a portion of the ordinary coal auger, it will be seen that my improved cutting bit is formed in two like sections or 90 pieces, which I have designated 10 and 10'. Each section consists of a transversely extending portion 11, one end of which is angularly bent, as at 12, these transverse portions being apertured, as at 13, for the 95 passage of an attaching bolt. The bit section 14 is integral with the transverse portion 11 but has a width equal to approximately half the length of this transverse portion, and each bit section is deflected to 100 one side from the plane of the transverse portion 11, as at 15, and then is slightly twisted to provide the bit proper 16. The inner edge 17 of each cutting portion 16 is approximately at right angles to the portion 11, but the outer edge 18 extends outward and downward. The lower edge 19 is beveled or ground to form a cutting edge and

105 when the two bits are assembled, it will be seen that the cutting edges of the two bits 110

are reverse to each other and that these cutting edges extend upward and outward from the adjacent edges of the two bits.

Coacting with the cutting blades 14 are 5 wings 20 designed to form continuations of the valleys or threads of the auger and cause the coal to be elevated to said threads and carried upward by them. Each of these wings 20 is integral with a base plate 21 which lies flat against the transverse member 11, the blank from which this part is 10 made being bent to provide the wing 20 which extends downward at an angle of about 45° to the upper edge face of the base 15 21. The wing extends below the base plate 21 and the inner edge of the wing is inwardly and downwardly curved, as at 22. The base plate 21 beyond the wing is inwardly flanged, as at 23, to extend beneath 20 the portion 11 and lie against turning movement. Passing through the flattened end *a* of the auger A and through the transverse portions 11 is a bolt 24 having a head on one end and carrying a nut 25 on the 25 opposite end.

It will be seen that the flattened end *a* of the auger is formed at its junction with the twisted portion of the auger with a shoulder *a'*. An ordinary coal auger may be 30 readily flattened by a blacksmith or it may be flattened by dies. It will be understood that under some circumstances the wings 20 may be left off. Thus, for instance, where the auger is being used for drilling in a 35 horizontal plane or where the auger is drilling upward, as in the roof of the mine or at an upward inclination to the breast of the coal, these wings will be omitted. It will be noted that with this device the wings 40 may be applied or omitted as desired.

It will be seen that bits of this character may be very cheaply made of high duty steel, that they may be readily applied to all types and makes of coal augers, and that 45 after long usage they can be renewed by filing or grinding, or that new bits may be disposed upon the augers in place of the old bits at any time. Thus augers equipped with these bits will last indefinitely. It will 50 further be obvious that the services of a blacksmith in constantly sharpening augers is done away with, while at the same time a much superior bit is produced.

One of the advantages of the detachable 55 bit which forms the subject matter of this application is that it does not have to fit the twist of the auger. Inasmuch as augers have many different pitches, it is impossible to make detachable bits which will fit the 60 twists of all augers, but by providing my bit and flattening the end of the auger, the bit is applicable to all augers no matter what the twist may be.

I claim:—

65 1. A detachable bit for coal augers formed

in two opposed complementary sections together adapted to embrace and clamp the auger between them, each section comprising a transversely extending auger-clamping portion and a blade having a width equal 70 to approximately one-half of the length of the clamping portion, the blades being twisted in opposite directions and each having a cutting edge, and wings carried by each section in advance of the corresponding blade and extending downward and laterally diagonally to the longitudinal axis of 75 the blade and adapted to form continuations of the auger, and a bolt passing through the sections and adapted to pass through the 80 auger.

2. A detachable bit for coal augers formed in two opposed complementary sections together adapted to embrace and clamp the auger between them, each section comprising 85 a transversely extending auger-clamping portion angularly bent at one end, an integral blade having a width approximately equal to one-half the length of the clamping portion and extending downward toward 90 that end of the clamping portion remote from the angular end, the blades being twisted and the inner edges of the two blades being in approximate contact and in alignment with the longitudinal axis of the auger, 95 a wing carried by each section in advance of the blade and extending downward and laterally diagonally to the longitudinal axis of the blade and forming continuations of 100 the auger, and a bolt passing through the sections and adapted to pass through the auger.

3. A detachable bit for coal augers formed in two opposed complementary sections together adapted to embrace and clamp the 105 auger between them, each section comprising a transversely extending auger-clamping portion angularly bent at one end, an integral blade having a width approximately equal to one-half the length of the 110 clamping portion and extending downward from that end of the clamping portion remote from the angular end, the blades being twisted and the inner edges of the two blades being in approximate contact and in 115 alignment with the longitudinal axis of the auger, wings associated with each blade, each wing comprising a base plate fitting against the transversely extending clamping portion of the blade and having a flange 120 engaging with an edge of the said clamping portion, an integral wing portion extending approximately at right angles to the base plate and extending downward and at an angle to the longitudinal axis of the blade 125 and constituting a continuation of the auger, and a bolt passing through the base plates of the wings and through the clamping portions of the bit and adapted to pass through 130 the auger.

4. A detachable bit for coal augers formed in two opposed, complementary sections adapted when placed together to form a relatively narrow, parallel-sided auger-clamping portion, each section having a blade, the blades being twisted in opposite directions and each having a cutting edge, and a bolt passing through the sections and adapted to pass through the auger.
- 10 5. A detachable bit for coal augers formed in two opposed, complementary sections adapted when placed together to clamp the auger between them, each section comprising a transversely extending auger-clamping portion, and a blade having a width equal to approximately one-half of the length of the clamping portion; the blades of the two sections being twisted in opposite directions and each having a cutting edge.
- 15 6. A detachable bit for coal augers formed in two opposed, complementary sections adapted together to embrace and clamp the auger between them, each section comprising a transversely extending, flat, auger-clamping portion angularly bent at one end, an integral blade having a width approximately equal to one-half the length of the
- clamping portion and extending downward from that end of the clamping portion remote from the angular end, the blades being twisted and the inner edges of the two blades being in approximate contact and in alignment with the longitudinal axis of the auger, and a bolt passing through the clamping portions of the sections and adapted to pass through the auger.
- 20 7. The combination with a coal auger having a flattened, perforated extremity, of a detachable bit formed in two opposed, complementary sections together adapted to embrace and clamp the flattened portion of the auger between them, each section comprising a transversely extending, flat, auger-clamping portion angularly bent at one end, a blade carried by each section, the blades being twisted and the inner edges of the two blades being in approximate contact and in alignment with the longitudinal axis of the auger, and a bolt passing through the clamping portions of the sections and through the aperture in the auger.

In testimony whereof I hereunto affix my signature.

FRED McLAUGHLIN.
